WEFT DETECTOR

Application filed June 27, 1929. Serial No. 374,124.

This invention relates to improvements of weft detectors of the side slipping type for looms and it is the general object of the invention to provide a detector which will not slip to give premature indication of weft if the shuttle be improperly placed.

The yarn engaging finger or arm of a weft detector is usually so placed as to be received by a slot in the binder of the lay as the latter moves forwardly. There is also a slot in the shuttle through which the detector finger moves when the shuttle is properly placed. If the shuttle has rebounded, however, the detector finger may engage the solid wall of the shuttle and slide along the same to give improper indication. It is an important object of my present invention to provide a guard operative to engage the shuttle when improperly boxed and prevent side slipping of the detector.

Weft detectors of the side slip type are usually so mounted as to move around a relatively fixed pivot when giving indication of weft exhaustion. The offset of the yarn detecting surface relatively to the pivot must exceed a certain critical angle before side slipping movement can take place on a bare bobbin. It is a further object of my present invention to provide a weft detector having the usual yarn engaging surface placed so that it can slide at exhaustion of weft together with an auxiliary surface placed with respect to the pivot so as to prevent angular movement of the detector even though the auxiliary surface or guard be in contact with a smooth surface, such as the side wall of a shuttle.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a top plan view of an end of the lay with parts removed showing my improved form of detector in engagement with a full supply of weft,

Fig. 2 is a view similar to a portion of Fig.

1 but with the detector in engagement with a solid portion of the shuttle,

Fig. 3 is a view similar to Fig. 2 but showing the auxiliary detector or guard in engagement with the rings of the bobbin,

Fig. 4 is a section on line 4—4 of Fig. 1,

Fig. 5 is a view similar to Fig. 4 but showing the relation of a detector with respect to a substantially empty bobbin,

Fig. 6 is a section on line 6—6 of Fig. 2,

Fig. 7 is a perspective view looking from the front showing the guard,

Fig. 8 is a detailed vertical section on line 8—8 of Fig. 3, and

Fig. 9 is an enlarged view looking in the direction of arrow 9, Fig. 1.

Referring particularly to Fig. 1, I have shown the lay 10 having a box front 11 and box back 12 between which is located the shuttle S. The box front is provided with a slot 13 through which the detector to be described may extend. I have shown my invention adapted to a form of loom wherein the shuttles run on their sides so that transfer may take place horizontally.

The breast beam 14 has secured thereto a stand 15 to which is secured by means of bolts 16 a detector base 17. The latter has slidably mounted therein a carrier 18 to which is pivoted as at 19 a detector arm 20. The latter has a forwardly extending tail 21 to which is pivotally connected a controller rod 22. This rod extends to the left as shown in Fig. 1 and is normally out of cooperative relationship with respect to an actuating floating lever 23. The latter is pivoted on a stud 24 carried by a vertically reciprocating block 25. The controller has a forwardly bent end 26 and for the purposes of the present invention it is sufficient to state that when end 26 is to the right of the adjacent end of the actuator lever 23 as viewed in Fig. 1 the loom will continue to operate with the same supply of weft, but when the controller end 26 is moved to the left to the dotted line position indicated at 27 under the adjacent end of the lever 23 a change in the operation of the loom will be initiated.

A compression spring indicated at 28 in dotted lines in Fig. 1 acts to move the de-

6 tector arm or finger 20 rearwardly, and the later by engaging a pin 29 on the slide 18 will cause the latter also to move rearwardly under normal conditions. The rear end of the finger 20 is notched as at 30 and may be made relatively thin as indicated in Fig. 9 at 31.

10 In operation when a sufficient supply of weft is present the detector arm will move forwardly against the action of spring 28 and the finger or arm 20 will undergo substantially no angular movement relatively to slide 18. Under these conditions the controller 22 will remain at rest and there will be no change in the operation of the loom resulting from the feeler. When insufficient weft is present, however, the teeth 30 will not be held by the arm and will slide along the substantially denuded bobbin B because of the fact that the roughened or notched surface 30 is offset in the direction of the length of the bobbin with respect to the axis 19 about which the detector swings. The offset is sufficient so that the detector will be given a decided lateral movement to effect sufficient movement on the part of the controller with respect to the actuator lever 23.

15 The matter thus far described of itself forms no part of my present invention, the floating lever 23 operating in a manner similar to that set forth in patent to Ryon No. 1,030,748.

20 As previously stated there are times when the detector teeth 30 will engage a surface other than the bobbin, such for instance, as when the shuttle is improperly positioned. Under these conditions the detector teeth may engage either the rings 40 of the bobbin B or the upright wall 41 of the shuttle. In such cases the detector would ordinarily move in a clockwise direction around the stud 19 and give an improper indication of weft exhaustion. In order to prevent this I provide a guard 50 shown particularly in Fig. 7. The guard is formed preferably of pressed sheet metal, having an open forwardly extending bearing 51 having top and bottom portions 52 and 53, respectively, between which is adapted to extend the arm 20. These portions of the bearing are connected together as at 54 so that said bearing may be made of a single piece of metal. The top 52 is provided with a pair of threaded openings 55 adapted to receive screws 56 as shown for instance in Fig. 3 for the purpose of clamping the bearing 51 against the arm 20.

25 Secured to the rear part of the bearing 51 is a vertical wall 57 from which rearwardly extend upper and lower horizontal plates 58 and 59, respectively. These plates are spaced apart a distance somewhat less than the diameter of the yarn of a full bobbin and their rear edges may be corrugated or scalloped as at 60. The scalloped edges are placed at a sufficient distance from the teeth

30 so that when the bobbin is full of weft the teeth will be out of contact with the yarn. The plates are spaced by a distance greater than the bobbin diameter when bare so that the teeth 30 will be permitted to engage the bobbin. The space 61 located between the top and bottom portions 52 and 53 of the bearing aligns with a corresponding opening 62 formed in the wall 57 and shown particularly in Fig. 8. By this construction I am enabled to slip the guard or auxiliary detector over the arm 20 without deforming the latter.

35 Referring particularly to Fig. 1 it will be noted that the left hand ends of the upper and lower plates 58 and 59 extend toward a line passing through the stud 19 normal to the surface being detected. The slight angle existing between this normal line and the line passing from the stud 19 to the left end of the plates 58 and 59 will be so small as to prevent side slipping movement of the detector should the said plates engage a smooth surface.

40 In operation when sufficient weft is present and the shuttle is properly boxed the parts will assume the position shown in Fig. 4 and the rear scalloped edges 60 which are smooth to prevent abrasion of the yarn will engage the weft of the full bobbin to prevent contact of the teeth 30 of the detector with the weft. Under these conditions there will be no tendency for the arm 20 to move along the bobbin even though the rear edges of said plates be smooth because of the fact that the angle of offset is too small. As previously suggested when the weft is substantially exhausted the teeth 30 will be permitted to engage the substantially denuded bobbin B as set forth in Fig. 5, sliding along the bobbin to give indication of exhaustion. In this case the plates are not in contact with the bobbin and the teeth 30, being sufficiently offset from the axis of the detector, may slide along the depleted bobbin.

45 If the shuttle should be slightly misplaced as suggested in Fig. 3 with the butt of the bobbin opposite the detector the rings 40 will engage the scalloped edges 60 to prevent side slipping movement of the detector. While I have shown these edges 60 as being scalloped yet this is not deemed necessary in view of the small angle of offset previously referred to. Should the shuttle be more widely misplaced the plates 58 and 59 will be permitted to engage the wall 41 of the shuttle and indication under these conditions will be prevented as is also the case described in connection with Fig. 3.

50 From the foregoing it will be seen that I have provided a simple attachment for side slipping weft detector readily removable by means of screws 56 and so constructed as to have with the axis of the detector so small an angle of offset as will prevent side slipping of

said guard should the latter engage a smooth surface. It will further be seen that the guard is so constructed that it does not interfere with the correct operation of the detector 5 relatively to the yarn on the bobbin B.

Having thus described my invention it will be seen that changes and modifications may be made therein by those skilled in the art without departing from the spirit and scope 10 of the invention and I do not wish to be limited to the details herein disclosed, but what I claim is:

1. In a weft detecting mechanism to detect a mass of weft which decreases in diameter as it approaches exhaustion, a detector member, 15 a pivot therefor around which the detector swings to give indication of weft exhaustion, said member having weft engaging elements offset in different degrees along the length of 20 the mass of weft relatively to the pivot, one element being offset in less degree than the other and effective to engage a large diameter only of weft to prevent the other element from engaging the weft, the offset of the first 25 element being too small to effect sliding of said element along the weft of large diameter, and the other element having a greater offset than the first element and effective to engage a relatively small diameter of weft and slide 30 therealong to move the member around the pivot when insufficient weft remains.

2. In a weft detecting mechanism to detect a mass of weft which decreases in diameter as it approaches exhaustion, a detector member, 35 a pivot therefor around which the detector swings to give indication of weft exhaustion, and two elements for the detector each capable of engaging the weft, one element to engage the yarn at such times only 40 as the weft is of relatively large diameter and at such times preventing engagement of the weft by the other element, said first element being incapable of sliding along the weft to cause angular motion of the detector around its pivot, and the other element effective to 45 engage weft when the diameter of the latter is relatively small, said other element being capable of sliding along the weft to cause angular motion of the detector around its pivot.

3. In a side slipping weft detecting mechanism to detect a mass of weft which decreases in diameter as exhaustion of weft approaches, a pair of yarn engaging elements connected and movable together as 55 a unit, one element to engage the weft when the latter is of relatively large diameter only, said element preventing the other element from engaging the weft when the latter is of large diameter and said first element being incapable of sliding movement along a large mass of weft, the first named element being incapable of engaging the weft when the latter has been diminished to a predetermined diameter, whereupon the second or 60 other element engages the weft to detect and

slide along the mass of weft at indication of weft exhaustion in the usual manner.

4. In a side slipping weft detecting mechanism to detect a mass of yarn the diameter of which decreases as exhaustion approaches, 70 a pair of weft engaging elements connected together to move as a unit, one element to engage a large diameter of weft only and the other element to engage a small diameter of weft only, the first element being incapable of sliding along the weft when in contact therewith and preventing engagement of the weft and other element when the weft is of large diameter, the other element when capable of engaging the weft acting 75 in the usual manner to slide along a depleted supply of weft to indicate exhaustion of weft.

5. In a side slipping weft detecting mechanism to detect a mass of yarn the diameter 80 of which decreases as exhaustion approaches, a pair of weft engaging elements one of which engages a large diameter of weft only to prevent engagement of the latter by the other element, the other element to engage the weft only when the weft diameter is too small to be engaged by the first element, the first element being incapable of moving along the weft when in contact therewith and the second element acting in the usual 85 manner to move lengthwise and in contact with a depleted weft supply to indicate weft exhaustion.

6. In a side slipping weft detecting mechanism to detect a mass of yarn the diameter 100 of which decreases as exhaustion approaches, a pair of weft engaging elements one of which engages a large diameter of weft only to prevent engagement of the latter by the other element, the other element to engage the weft only when the weft diameter is too small to be engaged by the first element, the first element being incapable of moving along the weft when in contact therewith and the second element acting in the usual 105 manner to move lengthwise and in contact with a depleted weft supply to indicate weft exhaustion, the first element being removable from the second element although normally secured thereto.

7. In a side slipping weft detecting mechanism to detect a mass of yarn the diameter of which decreases as exhaustion approaches, 115 a pair of weft engaging elements one of which engages a large diameter of weft only to prevent engagement of the latter by the other element, the other element to engage the weft only when the weft diameter is too small to be engaged by the first element, the first element being incapable of moving along the weft when in contact therewith and the second element acting in the usual manner to move lengthwise and in contact with a depleted weft supply to indicate weft exhaustion, the first element having spaced members which 120

lie one over and the other under the second element.

8. In a side slipping weft detecting mechanism to detect a mass of yarn the diameter of which decreases as exhaustion approaches, a pair of weft engaging elements one of which engages a large diameter of weft only to prevent engagement of the latter by the other element, the other element to engage the weft only when the weft diameter is too small to be engaged by the first element, the first element being incapable of moving along the weft when in contact therewith and the second element acting in the usual manner to move lengthwise and in contact with a depleted weft supply to indicate weft exhaustion, the first element having spaced members which lie one over and the other under the second element, said members extending behind the second named element.

9. In a side slipping weft detecting mechanism to detect a mass of yarn the diameter of which decreases as exhaustion approaches, a pair of weft engaging elements one of which engages a large diameter of weft only to prevent engagement of the latter by the other element, the other element to engage the weft only when the weft diameter is too small to be engaged by the first element, the first element being incapable of moving along the weft when in contact therewith and the second element acting in the usual manner to move lengthwise and in contact with a depleted weft supply to indicate weft exhaustion, said first named element being capable of assuming a plurality of positions relatively to the second member, being secured to the second element in each position.

10. In a weft detecting mechanism to detect a mass of weft which decreases in diameter as it approaches exhaustion, a detector member, a pivot therefor around which the member swings, and a pair of weft engaging elements on the member, one element effective to engage the weft when the same is of relatively large diameter but being so related to the pivot as to be incapable of sliding along a large diameter of weft to effect indication, and the other element effective to engage the weft when of a relatively small diameter only and being so related to the pivot as to slide at weft exhaustion to give indication of weft depletion.

In testimony whereof I have hereunto affixed my signature.

RICHARD G. TURNER.
